[57] CLAIM

The ornamental design for a carrying case with picnic utensils and supplies, as shown and described.

DESCRIPTION

FIG. 1 is a front elevational view of a carrying case with picnic utensils and supplies showing my new design;

FIG. 2 is a sectional view thereof taken along line 2—2 of FIG. 4;

FIG. 3 is a rear elevational view thereof;

FIG. 4 is a top, front and left side perspective view thereof;

FIG. 5 is a sectional view thereof taken along line 5—5 of FIG. 4;

FIG. 6 is an enlarged fragmentary view of the handle thereof; and,

FIG. 7 is a fragmentary view of FIG. 1 showing table cloth and napkins.
